UNITED STATES PATENT OFFICE

WILLIAM W. DEGLER, OF DAVIS, WEST VIRGINIA.

PIVOTED SWING HANGER.

Application filed March 31, 1923. Serial No. 629,157.

To all whom it may concern:

Be it known that I, WILLIAM W. DEGLER, a citizen of the United States, residing at Davis, in the county of Tucker and State of 5 West Virginia, have invented certain new and useful Improvements in Pivoted Swing Hangers, of which the following is a specification.

My invention relates broadly to supports, 10 and has particular reference to pivoted hangers, for swings, hammocks, or the like.

An important object of the invention is to provide a pivoted hanger of the above mentioned character, which may be maintained 15 suitably lubricated for a long period, thereby eliminating squeaking, in operation.

A further object of the invention is to provide a pivoted hanger of the above mentioned character, equipped with ball bearings, so constructed that they take radial and end thrusts, whereby the hanger may be 20 vertically disposed, or arranged at an angle, in use.

25 A further object of the invention is to provide a pivoted hanger of the above mentioned character, which is strong, durable, and will last practically indefinitely.

Other objects and advantages of the invention 30 will be apparent during the course of the following description.

In the accompanying drawings forming a part of this specification, and in which like numerals are employed to designate 35 like parts throughout the same,

Figure 1 is a side elevation of a pivoted hanger embodying my invention,

Figure 2 is an edge elevation of the same,

Figure 3 is a side elevation of the device, 40 parts being shown in central vertical section,

Figure 4 is a transverse sectional view taken on line 4—4 of Figure 1, parts broken away, and parts omitted, and,

45 Figure 5 is a detail section taken on line 5—5 of Figure 3.

In the drawings, wherein for the purpose of illustration is shown a preferred embodiment of my invention, attention being 50 called first to Figures 1 to 5, inclusive, the numeral 10 designates a body portion, hanger block, or housing, preferably in the form of a casting. This body portion 10 is provided at its upper end with flanges 11, 55 through which screws 12 may be passed, for engagement with a horizontal support 13,

such as the ceiling of a porch. The numeral 14 designates a screw, which has its head anchored or embedded in the casting 10, and this screw is adapted for engagement with 60 the support 13. It is obvious that the screw 14 may be used alone or with the screws 12. The invention is not restricted to the employment of screw or screws as attaching means, as any other suitable means may be 65 employed for this purpose, such as bolts.

The body portion or housing 10 is provided upon its opposite sides with preferably cylindrical chambers 15, formed therein, for the reception of ball bearings. These 70 ball bearings comprise race-ways or guides 16, receiving balls 17, held therein by retainers 18, as shown. The race-ways 16 engage at their inner ends, an annular flange 19, forming a central feed chamber 20 for 75 grease or other lubricant, which is fed to the ball bearings, as will be described. The chambers 15 and 20 form a recess extending through the hanger block from one side to the other.

80 The numeral 21 designates a grease cup, secured to the body portion or housing 10 and discharging into a port 22 formed therein, which is in communication with the central feed chamber 20, as shown.

85 The numeral 23 designates a pivot suspension pin, provided at one end with a head 24. Carried by the pin 23 is a thrust ring 25, having at its inner end a ball receiving groove or race-way 26, arranged obliquely. 90 The pin 23 has a portion of its length, outwardly of the ring 25, slightly reduced in diameter, and screw threaded, for receiving thereon a coacting thrust ring 27, provided at its inner face with a ball receiving groove 95 or race-way 28, arranged obliquely. The race-ways 26 and 28, face inwardly, and are arranged opposite to each other, and engage with the balls 17, as shown. The thrust rings 25 and 27 coact with the ball 100 bearings, constituting ball bearing devices for taking both radial and longitudinal thrusts. As the screw threaded portion of the pin 23 is slightly reduced in diameter, the same does not contact with the race-ways 15, but are spaced therefrom, and this permits the grease within the central feed chamber 20 passing to the balls in the ball bearings, to retain them suitably lubricated.

105 The numeral 29 designates a swinging member or yoke, preferably embodying sides 30, the lower ends of which are apertured for

receiving threaded shanks 31, carried by a transverse member or boss 32, having an eye 33 formed thereon. The threaded shanks 31 carry nuts 34, having screw threaded engagement therewith, and lock washers 35 are preferably arranged between these nuts and the sides 30, to lock the same together. It is thus seen that the sides 30 are rigidly connected with the transverse member or boss 32, but may be separated therefrom, when desired. The upper ends of the sides 30 are provided with enlarged preferably circular heads 36. These heads have openings 37 formed therein. The head 36 to the 10 left, Figure 1, is arranged between the head 24 of the pin 23 and the thrust ring 25, while the head 36 to the right is arranged between the thrust ring 27 and a nut 38, having screw threaded engagement with the screw 15 threaded portion of the pin 23. Any suitable means may be employed to prevent accidental rotation of this nut 38, such as a cotter pin 39. Means are provided to prevent the heads 36 turning upon the pin 23, and to accomplish this, these heads are provided with inwardly projecting keys or extensions 40, adapted to enter a longitudinal groove 41, formed in the pin 23. In order that the grease may not work outwardly 20 from the bearings, I arrange washers 42, such as felt washers, between the keepers 18 of the ball bearings, and the heads 36.

In view of the foregoing description, it is 25 obvious that I have provided a hanger, which will operate without noise, which is strong and very durable. The pivoted yoke 29 will turn about the axis of the pin 23, with the least friction, by virtue of the ball bearing devices. The arrangement of the 30 race-ways of the ball bearing devices, provides means whereby these devices serve to take up radial and longitudinal thrust.

This permits of the hanger being supported vertically, as illustrated in Figure 1, or the same may be arranged diagonal, as when 45 it is employed to support a hammock. The swing or the like is suspended from the eye 23, as is obvious.

It is to be understood that the form of my invention herewith shown and described 50 are to be taken as a preferred example of the same, and that various changes in the shape, size, and arrangement of parts may be resorted to without departing from the spirit of my invention or the scope of the 55 subjoined claim.

Having thus described my invention, what I claim is:

A hanger block to be secured to a support and having a recess formed therein extending from one side thereof to the other, said recess having an internal annular flange arranged centrally thereof, a grease cup attached to the central portion of the block to supply grease to the recess at its center, race ways mounted within the end portions of the recess and engaging the sides of the internal flange, balls held within the race ways, a pivot suspension element passing through the recess and race ways, radial and end thrust rings mounted upon the pivot suspension element upon the outer side of the race ways and engaging the balls, a hanger element embodying side plates arranged in close relation to said sides and 75 apertured for receiving the pivot suspension element, packing arranged between said sides and the side plates, and means carried by the pivot suspension element for holding the side plates in proper contact 80 with the packing.

In testimony whereof I affix my signature.

WILLIAM W. DEGLER.
